UNITED STATES PATENT OFFICE.

ANTHONY P. FERN, OF DUNKIRK, NEW YORK.

MUSIC-LEAF TURNER.

1,311,765.

Specification of Letters Patent. Patented July 29, 1919.

Application filed October 25, 1918. Serial No. 259,666.

To all whom it may concern:

Be it known that I, ANTHONY P. FERN, a citizen of the United States, residing at Dunkirk, in the county of Chautauqua and State 5 of New York, have invented certain new and useful Improvements in Music-Leaf Turners, of which the following is a specification.

This invention relates to music leaf turners, and the object thereof is to provide a 10 simply constructed and efficient apparatus of this character which may be used in connection with any piano or on any music stand and in which the turning mechanism is actuated by keys operable at points remote.

15 Another object is to provide an apparatus of this character having simple and efficient leaf turning members operated automatically on the releasing of a catch.

With the foregoing and other objects in 20 view, which will appear as the description proceeds, the invention resides in the combination and arrangement of parts and in the details of construction hereinafter described and claimed, it being understood that 25 changes in the precise embodiment of the invention herein disclosed may be made within in the scope of what is claimed without departing from the spirit of the invention.

In the accompanying drawings:

30 Figure 1 represents a front elevation of a portion of a piano showing this improved music leaf turner applied.

Fig. 2 is a vertical section taken on the line 2—2 of Fig. 1.

35 Fig. 3 is a detail vertical section through the lower portion of the apparatus,

Fig. 4 is a vertical detail section taken on the line 4—4 of Fig. 3, and

40 Fig. 5 is a front elevation on a small scale showing the turner constituting this invention detached.

Fig. 6 is a detail sectional view.

In the embodiment illustrated, the turner 45 constituting this invention comprises a supporting or backboard 1 having a laterally and forwardly projecting flange 2 at its lower edge on the bottom of which is mounted a strip 3 covered by an anti-friction material, 4, and which is designed to rest on the 50 music shelf S of a piano as is shown clearly in Fig. 2. A strip 5 of felt or other suitable anti-scratching material is secured to the rear face of the board 1 at its upper edge (see Fig. 2).

55 Depending from flange 2 are a plurality of hangers 6 having rearwardly and lat-

erally extending apertured lugs 7 for attachment to the lower face of the flange 2 and forwardly extending arms 8 at their lower ends. Four of these hangers 6 are 60 here shown, although obviously any desired number may be used, and they have nuts 8' and screws 8" to prevent tilting of the board.

A rod 10 is supported midway the length of flange 2 and is mounted in an apertured 65 ear 11 projecting laterally and forwardly from the upper edge of board 1 as is shown clearly in Fig. 1. This rod 10 has a knob 12 at its upper end and is provided at points below said knob with collars 13 which are 70 designed to support hinge members herein-after to be described.

Leaf supporting frames 14 are hingedly connected with the rod 10 any desired number of which may be employed, two being 75 here shown. Each of these frames comprises an upright outer bar 15 connected with an inner bar 18 by cross bars 16 and 17 which form the top and bottom members of the frame. The top and bottom members 16 and 80 17 and the inner member 18 of each frame has an inturned laterally spaced flange 19 to form receiving pockets for the sheets or leaves L to be supported by said frames.

The inner bars of the frame members have 85 hinged knuckles 20 and 21 which are pivotally engaged with the rod 10 which form the pintle for connecting the frames. The upper hinge knuckles 20 are designed to rest on and be supported by the collars 13 carried 90 by rod 10. Arranged above the lower knuckles 21 are coiled springs 22 and 24, the spring 22 being connected at one end with the rod 10 and having a laterally extending finger 23 which engages the rear face of the 95 rear frame member 18 as is shown clearly in Fig. 1, while the spring 24 has a similar finger 25 which engages the rear face of member 18 of the other frame, so that these springs exert their tension normally to turn 100 these frames toward the left.

Catch members 26 are pivotally mounted in brackets 27 carried by the flange 2 and are positioned to engage the respective frames to hold them open against the tension of the 105 springs 22 and 24. Springs 28 are arranged below these catches 26 to force them upwardly into engagement with the lower frame members 17 as is shown clearly in Fig. 4 of the drawings. Wires or other suitable 110 connecting elements 29 are attached at one end to the noses of the catches 26 and at

their other ends are secured to rods 30, two of which are here shown, one for each catch member. These rods 30 are mounted for vertical movement in bearings 31 carried by the 5 brackets or hangers 6.

Rods 32 are mounted in the hangers 6 between the laterally extending arms 8 thereof and said bearings 31 as is shown clearly in Fig. 3. Coiled springs 33 are mounted on 10 these rods and between their upper ends and the bearings 31 are disposed the ends of cross rods 34, two of which are here shown, said springs exerting their tension to force said rods 34 upwardly.

15 Connectors in the form of metal plates 35 connect the rods 30 and 34 so that when one of these rods is moved the other will be moved simultaneously therewith for a purpose presently to be described.

20 T-shaped metal castings 36 are carried by the rods 34 said rods extending through the heads of these castings and having recesses 37 in their heads to receive the connectors 35 as is shown clearly in Fig. 3. The shanks 38 of these castings are also provided with longitudinally extending bores or sockets to receive rods 39 which are adjustably mounted in said sockets and held in adjusted position by set screws as 40. The lower ends of 30 these rods 39 have laterally extending feet 41 which are designed to rest on the keys K of a piano as shown in Fig. 1 to position them for ready depression by the operator when it is desired to turn a sheet of music.

35 In the use of this music leaf turner, when applied to a piano as shown in Figs. 1 and 2, the board 1 is supported on the shelf S with the feet 41 carried by the T-shaped members 36 resting on two of the keys K in 40 convenient position for actuation by the performer, and when it is desired to turn a sheet of music all that is necessary is to depress the foot 41 which causes the rod 34 on which the T-shaped member 36 is mounted to be forced downwardly against the springs 33 and through the connector 35 moves rod 30 downwardly, thereby exerting a pull on the wire 29 and releasing the catch 26 from the frame which carries the sheet 50 of music to be turned. Immediately this catch is released the frame will be swung toward the left by the spring connected therewith which is mounted on the rod 10, and thus the opposed face of the sheet or 55 leaf L will be exposed to view, as well as the face of the adjacent leaf.

It will thus be seen that with a music leaf turner constructed as above described, the frames 14 which are designed to hold the 60 leaves L will expose both faces of each leaf, first one and then the other.

While the T-shaped members 36 are here shown provided with feet 41 resting on the piano keys, they may obviously be connected 65 with any suitable actuating devices located

at a point remote, and be operated by the foot of the performer if found desirable to do so, and which will be necessary when the turner is mounted on a stand as shown in Fig. 5, the feet 41' there shown being connected with the catches by means of wires or flexible cables 42 which lead through guides 43 on the stand 44 to the catch members 26. It will be obvious that when these actuating feet 41 or 41' are released, that 70 the springs 33 will automatically return the rods 34 and 30 to normal position and the springs 28 will force the catches 26 upward into position for engagement with the frames 14 when the latter are swung laterally toward the right for resetting them. 75

The foregoing description and the drawings have reference to what may be considered the preferred or approved form of my invention. It is to be understood that I 80 may make such changes in construction and arrangement and combination of parts, materials, dimensions, etc., as may prove expedient and fall within the scope of the 85 claimed invention.

Having thus fully described my invention, what I claim as new and desire to secure by Letters Patent, is:

1. A music leaf turner comprising a supporting base having a laterally extending 90 flange, leaf carriers pivotally mounted on said base, spring pressed catches positioned to engage said carriers to hold them against turning, means for automatically turning said carriers when said catches are released, 95 vertically movable horizontally disposed rods connected with said catches, and means for lowering said rods to release said catches.

2. A music leaf turner comprising a supporting board, having a laterally extending flange at its lower edge, and an apertured ear at its upper edge extending forwardly; a pintle mounted in said flange and ear, leaf carriers mounted to swing on said pintle, coiled springs carried by said pintle and engaging said carriers to swing them in one direction, spring pressed catches for holding said carriers against the tension of said springs, horizontal rods mounted for vertical movement below said flange and parallel therewith, connections between said catches and rods, and adjustable means for lowering said rods to release said catches. 110

3. A music leaf turner comprising a board having a laterally extending flange at its lower end, brackets depending from said flange, upright rods mounted in said brackets having coiled springs thereon, vertically movable horizontally arranged rods carried by said upright rods above said springs, leaf carriers pivotally supported by said board to turn in a horizontal plane, spring catches for engaging said carriers to hold them against turning, connections between said catches and horizontally disposed rods, and 125 130

means for releasing said catches by depression of said rods.

4. In a music leaf turner, leaf carriers mounted to turn in a horizontal plane, 5 spring pressed catches for holding said carriers against turning, a pair of vertically spaced rods mounted for vertical movement, a connection between one of said rods and said catches, means connecting said rods 10 whereby they move in unison, springs en-

gaging the lower rod to move it upwardly after actuation, and a hanger carried by said lower rod and having means for exerting a downward pull thereon.

In testimony whereof I affix my signature 15 in presence of two witnesses.

ANTHONY P. FERN.
